CLAIM

The ornamental design for a housing for an electrical connector, as shown and described.

DESCRIPTION

FIG. 1 is a perspective view of a housing for an electrical connector showing our new design;

FIG. 2 is a top plan view thereof;

FIG. 3 is a front elevational view thereof;

FIG. 4 is a bottom plan view thereof;

FIG. 5 is a right side elevational view thereof, the left side being a mirror image;

FIG. 6 is a rear elevational view thereof;

FIG. 7 is a perspective view of a housing for an electrical connector showing a second embodiment of our new design;

FIG. 8 is a top plan view thereof;

FIG. 9 is a front elevational view thereof;

FIG. 10 is a bottom plan view thereof;

FIG. 11 is a right side elevational view thereof, the left side being a mirror image;

FIG. 12 is a rear elevational view thereof;

FIG. 13 is a perspective view of a housing for an electrical connector showing a third embodiment of our new design;

FIG. 14 is a top plan view thereof;

FIG. 15 is a front elevational view thereof;

FIG. 16 is a bottom plan view thereof;

FIG. 17 is a right side elevational view thereof, the left side being a mirror image;

FIG. 18 is a rear elevational view thereof.
